UNITED STATES PATENT OFFICE.

ROBERT DANIEL BRADFORD, OF LONDON, ENGLAND.

ROTARY AND RECIPROCATING INTERNAL-COMBUSTION ENGINE.

1,207,846.

Specification of Letters Patent. Patented Dec. 12, 1916.

Application filed November 27, 1914. Serial No. 874,249.

To all whom it may concern:

Be it known that I, ROBERT DANIEL BRADFORD, a subject of the King of Great Britain and Ireland, residing at 43 Lissenden Mansions, Highgate Road, London, England, have invented new and useful Improvements in Rotary and Reciprocating Internal-Combustion Engines, of which the following is a specification.

10 This my invention relates to internal combustion motive power engines of the kind in which the pistons and the parts movable with them do not rotate but reciprocate and carry reciprocating rollers which engage helicoidal grooves in a cam-member caused to rotate by the pressure of the rollers upon the sides of the grooves and to serve as a power transmitting means or fly-wheel.

20 The special features of the invention comprise air-feeding hollow piston rods coöperating with valved pistons to serve as admission and charging valves, cylinder heads which serve as exhaust and scavenging valves, a rotary cam-member surrounding the cylinder and pistons and having cam grooves which in addition to receiving the thrust of the pistons for causing the cam-member to rotate, also time the working of the engine in a new cycle.

25 30 Other features of novelty and utility will be apparent from the following description of an example of my invention.

Referring to the accompanying drawings: Figure 1 is a longitudinal section view of the engine. Fig. 2 is a plan view, a part being removed. Fig. 3 is an end view of the engine seen from the right hand of Fig. 1. Fig. 4 is an end view of the engine seen from the left hand of Fig. 1. Fig. 5 is a diagrammatic development of the helicoidal grooves of the cam-member. Fig. 6 is a central longitudinal section through a part of a modified construction of engine according to this invention and Fig. 7 is a sectional end view of the same.

Referring now to Figs. 1 to 5, the engine selected for description and illustration by way of example of an embodiment of this invention comprises a cam-member A rotatable on balls H and S about a cylinder B. The said cam-member A is, in fact, a reticulated structure having ribs A¹ intersecting and integral with helicoidal guides or ways or grooves A² and is provided with ball-races H¹, S¹ and also with a portion A³ for attachment say to the part to be driven, for

example the drum 67 which may be used as a driving pulley. The cam-member A is mounted eccentrically about the cylinder B, being carried on ball-races H², S² carried by the eccentric ends C¹, C² of the stationary cylinder water-jacket C. Projecting outwardly beyond the ball-races H², S² are screwed portions of the said stationary water-jacket C¹, C² and these are utilized for attaching the engine to the vehicle or other body, to be propelled by it for example, by means of collars 23 having lugs 24, (Figs. 1 to 4,) for attachment say to the frame spars of an aeroplane. Between the water-jacket C and the cam-member A the piston guide-bars G work in a guide G¹ parallel to the cylinder axis, the said guide G¹ being carried by the eccentric water-jacket ends C¹, C² to which it is affixed. See Figs. 1, 75 3 and 4. This guide G¹ is carried in correspondingly shaped apertures of the eccentric ends and secured against longitudinal movement by means of a ring C³ at the right hand end which ring C³ is screwed to the end C² and which has a depending lug C⁴ shaped to engage slots G² cut in the sides of the said guide G¹ at the top. In assembling the parts of the engine the ring C³ is first screwed ready to the position shown. 85 The guide G¹ is then inserted into position and the ring C³ rotated until the abutment portion of it engages the said slots G². The ring is then suitably secured in place. 90

Each guide-bar carries a compound roller N mounted on ball-bearings N¹ as shown in Fig. 1 and adapted to run in the helicoidal grooves A² and by transmitting the force exerted on the piston to the inclined sides 95 of the said grooves A² to cause the rotation of the cam-member A. One of the rollers N transmits pressure upon the grooves A² in one direction and the other roller N transmits the pressure in the other direction. The 100 journals supporting these ball bearings are turned eccentrically one to the other, while at places in the grooves where the change of pressure takes place sections of the said grooves are made adjustable to render this 105 change noiseless in the following manner: The sides of the grooves are provided at points where required with movable sections similar to that shown at 1^a, Fig. 2 secured to the cam-member A by means of taper-headed screws 2^a. As the inclined guiding surface 3^a wears away, the worn sections are 110

set inward by removing, say by scraping some of the material from the outer side of the counter-sunk screw holes so that the screw-heads may be allowed to penetrate farther into the plate 1^a and so to press upon the opposite side 4^a of the hole and force the plate 1^a inward. The outer end of each guide-bar G carries a depending bracket Q¹ into which the outer end of the hollow piston rod Q is screwed. The bracket Q¹ is secured to the guide bar G by means of a stepped end on the latter which has an abutment G² for securing the said bracket Q¹ against relative endwise movement. The bracket is fixed on the guide-bar by sliding these parts laterally into an engagement in which they are retained by the sides of the guide G¹. The piston proper suitably attached to the piston rod Q is formed at its periphery with a flexible corrugated lip or margin E¹, owing to its corrugated formation adapted to yield to fluid pressure from within the cylinder and formed also with pillars E² upon which is secured by means of screws a diaphragm D which bends about the pillars E² or moves axially on the screws E³ to allow the passage of air, from the hollow piston rod Q, around the inner end of the latter into the space E between the piston proper and the diaphragm D and thence into the cylinder between the pistons by way of the passage between the flexible margin of the piston and the said diaphragm.

An alternative to this piston just described is illustrated in Fig. 6. Here the hollow piston-rod 5^a is formed with a solid head 6^a provided with the usual piston rings 7^a. Near its periphery the piston is pierced to provide passages 8^a, 8^a, closed when the piston moves outward by means of a ring-valve 9^a which opens on the inward stroke and lies against supports 10^a fixed to the piston. At the inner face of the piston a disk-valve 11^a covers the inner end 12^a of the piston rod 5^a on the inward stroke and on the outward stroke it bends at its center or moves bodily, opens and rests against supports 13 so that air may pass from the hollow piston rod 5^a around the end 12^a and supports 13 into the cylinder. There are two pistons, both alike, having slide-bars G working in the guide G¹ and carrying rollers N, N for engaging the grooves or ways A², as above described, and the said ways are so arranged in the cam-member A that they govern the relative speeds and positions of the pistons and by consequence the timing generally as will be hereinafter explained. The cylinder B is screwed at R to the water-jacket but is made a sliding fit in the other end of the said jacket at R¹ to allow for expansion and contraction of the parts and each outer end is closed at the proper times by a cover J seated on a flange J¹ at the end of the

cylinder. This cover J is adapted for movement from the flange J¹ to the piston when the latter is in the position of the left hand piston shown in Fig. 1 for the purpose of scavenging the burnt charge. For this purpose it is mounted on rods 14 which reciprocate in sleeves 15 cast or otherwise secured to the exhaust box M (see Figs. 1 to 4) secured to the cylinder end by its gapped flange M¹ which engages the corresponding gapped and undercut cylinder end and which are united at their outer ends by a piece 16 which holds them rigid. One of these rods carries a slotted cross-head 17 within which a roller 18 on a crank-pin 19 may work to reciprocate the said cover J. The crank pin 19 is carried by a short shaft 20 rotating in a bearing 21 formed in the exhaust box M at the end of the cylinder. At its outer end the shaft 20 carries a star-wheel T arranged so that its teeth may mesh with teeth 22 fixed at intervals upon the inner side of the cam-member A (see Figs. 1, 3 and 4). These teeth 22 at the proper time in each rotation of the drum A; give one reciprocation to the cover J.

Instead of a reciprocating cover a rotating one such as shown in Figs. 6 and 7 is sometimes employed. This valve J¹ has an oval periphery and rotates at the cylinder ends upon a seating 41 having an oval opening through it. A half turn of the valve is given at the required time by means of a worm wheel 42 on its sleeve which wheel is in mesh with a worm 43 on a short shaft 44 which is driven in the manner described above with reference to the shaft 20. In the half-turn of the valve J¹ it will be opened fully to the exhaust as shown in Fig. 7 and closed again. The shaft 20 at each end of the machine is furnished with a second crank 25 to which is connected, by means of a dog-link 26, the ram 27 (see Fig. 1) of a pump K employed to feed the engine with liquid fuel. The pump barrel 28 is screwed into the exhaust box casting at 29 and has an inlet valve 30. The outlet valve is a ball 2 seated in a chamber communicating by means of a passage 3 with an annular passage L surrounding the hollow piston rod Q and in addition to covering the passage 7 the said ball 2 also covers an annular passage 5 communicating by a passage 6 with the combustion chamber. (See Fig. 1). When the ram 27 is delivering a fuel charge through passage 7, highly compressed air issues from the passage 3 and meeting the fuel spread by the valve 2 vaporizes it and passes by way of the annulus 5 and passage 6 to the combustion chamber at that end of the cylinder. The ram 27 of the fuel pump K is furnished at its inner end with an expanding device designed to act after the manner of a

hydraulic piston-leather, pressing in a fluid tight manner against the wall of the pump barrel. To this end the said device comprises a thin corrugated conical cup 39 of 5 metal preferably formed in one with, or attached to the plunger 27. The corrugated formation of this device permits the enlargement of the open end during the pressure stroke so that its indented edge 40 may 10 make, with the pump barrel, a liquid tight joint, the efficiency of which increases with the pressure.

A compressed air reservoir 32 is provided for use in starting and is charged by the 15 supply arriving by the passage 3. When released for use the air confined in it is released by means of a handle 33 upon a spindle having an arm 34 which may be thus turned to force the valve 35 from its seat. 20 The annulus L surrounding the piston rod Q is open to the combustion chamber except at the time when the piston is approaching the end of its outer stroke. Then a collar or sleeve 36 fast on the piston rod closes it and 25 still further compresses the air within, already compressed chiefly by the movement of the piston proceeding from the opposite end of the cylinder. The facing ends of the 30 collar 36 and the corresponding part of the exhaust box M are shown as having annular slits or channels 37 and the said facing ends may be of serrated or undulating form, as shown in Figs. 6 and 7 to render the sides of the channels 37 expansible against the 35 piston rod Q and the sleeve 38 of the cover J.

Water is circulated between the jacket C and the cylinder B by means of the pump Y, (shown in detail in Fig. 1) the barrel 45 of which is secured to the end C² of the 40 water jacket C. The ram 46 is driven from the star wheel T¹ the shaft of which is furnished with a worm 47 (see Figs. 1 and 3); meshing with a worm-wheel W the shaft of which is carried by a bearing 49, and has 45 fast at its other end a pinion 50 in gear with a spur X the shaft of which is also journaled in the bearing 49 and which has a crank pin 52 working in a dog link 53 at the outer end of the ram 46. The inner end of the 50 ram 46 is furnished with a device similar in principle to that described for pumping fuel, but modified being corrugated so as to allow the expansion of an extended periphery by the pressure of the liquid being 55 pumped. The cooling water from the radiator or the like enters the barrel 45, Fig. 1, by way of the valve at 56 and is expelled past the valve at 57 through the elbow 58 into the space between the cylinder and the 60 water jacket C, thence returning to the cooler by way of the outlet at the other end of the jacket.

The lubrication of the engine is effected by means of the oil supply pump P. See 65 Figs. 1 and 3. This pump is furnished with

a shank 60 adapted to be screwed into the eccentric end C² of the water jacket C and is operated by means of the mechanism employed to drive the water pump Y, the part 54 of which has a lug 61 to which the outer 70 end of the pump ram 62 is attached. At each reciprocation of the ram 62 oil is drawn into the barrel 63 past the check valve at 64 and expelled by way of valve at 65 and pipe 66 into the trough-shaped guide G¹, between 75 the inner ends of the guide-bars G. Each time that the pistons, and consequently the guide-bars G, meet, the oil between the latter is squirted upward from between them against the inner surface of the rotating 80 drum 67 and, owing to the speed of rotation of the said casing, is evenly spread by centrifugal force as a layer around the said inner surface so that scoops 68, 68 (see Figs. 1 to 85 4) carried by the guide G, skim off oil from the said layer and conduct it to the guide G again, but to points where the outer ends of the guide-bars G take it and force it outward to the ends of the said guide G. Here it is conducted downward by chutes 69, 69, 90 which deliver it in the path of the air within the hollow piston rods Q at the outer end of each stroke as indicated in Fig. 1. Oil is thus taken together with the air used for combustion and distributed over all the internal working surfaces. The oil, which enters the guide G¹ between the guide-bars G and is raised as above described over the 95 said guide-bars each time they nearly meet, twice in a revolution, in spreading over the 100 inside of the drum 67 is intercepted by parts of the ribs of the cam-member A (see Fig. 1) to lubricate the rollers N and ball-bearings N¹, S¹, S², and H¹, H². Oil from the drum 67 also enters the spaces into which the star-wheels T, T¹ protrude and, creeping along the teeth 22 lubricates the said star wheels T, T¹, and thence creeping to the helical gear 47 (see Fig. 3) is transmitted by it to the pinion W and by the intermediate gearing to the dog-link 53 and crank 52. Oil 105 also creeps along the plunger 46 to lubricate it. Oil from the star-wheels T, T¹ also passes to the crank-pin 18 (see Fig. 1) which actuates the scavenger valve dog-link 17 and 110 thence along the guide-rod 14 to which the said dog-link 17 is attached and the U-shaped 115 part 16 to the other rods 14.

The mode of operation is as follows: Supposing air and fuel to be exploded in 120 the space between the movable cover J and piston body D at the left-hand end of the cylinder the piston is forced inward drawing with it the hollow rod Q and guide bar G and compressing a charge of air previously drawn in between the pistons. During this stroke the roller N, being forced in a direction parallel to the axis of the cam-member A, presses against one side of the groove A² and so causes the cam-member to 125 130

rotate. This stroke is made when the left-hand roller N is in that part of the groove between the points 8 and 9, shown in the development of the grooves, Fig. 5. During the first part of this stroke of the left-hand piston, the right-hand piston roller N was moving in that portion of its groove A² between 10 and 11 when the air compressed by the explosion stroke of the left-hand piston was being forced around the flexible edge E¹ of the right-hand piston into the combustion chamber there, and during the latter part of the stroke of the left-hand piston the roller of the right-hand piston moved between the points 11 and 12, both pistons then moving together and further compressing the air within the right-hand combustion chamber. At the end of the left-hand working stroke, the momentum of the cam-member A or kinetic energy stored in it during the said working stroke, returns the left-hand piston outward (see Fig. 5; portion of groove between points 9 and 10) until the end of this exhaust stroke is reached at point 10. At this point the right-hand piston, which has been stationary throughout the last-mentioned stroke, is driven outward by the explosion in its combustion chamber. The burnt gases are expelled during the exhaust stroke from the outward side of the left-hand piston around the edge of the cover J, which is pushed inward against the piston, at the end of the stroke, by the star-wheel T, turned by the teeth 22 to allow this (see Fig. 4). When the cover J has moved inward quite to the piston, all the explosion chamber, as shown in Fig. 1 between the piston and the said cover J, is open to the exhaust box M, and scavenging is complete. The cover J is then retracted to its seat by the further rotation of the star-wheel T. While this exhaust takes place a fresh charge of air is being sucked in through the hollow rod of the left-hand piston, the space E in the said piston, past the edge of the diaphragm D, into the cylinder between the pistons. The diaphragm lags owing to its inertia, sliding on the screws at E², E² so that narrow passages are provided between it and the inner end of the hollow rod Q and between its rim and the piston. Or the diaphragm may bend inward at its center about the screws at E², E². In the latter case the rim of the diaphragm does not fit the piston tightly. During the movement inward of the left-hand piston corresponding with 10 to 11 the right hand piston compresses the charge of air within the space between the pistons, its travel corresponding with that part of its groove marked 8 to 9 (its explosion stroke), this stroke being made partly while the left hand piston is moving inward to meet the right hand piston be-

tween the points 10 and 11, and while scavenging, due to the movement of the cover J, takes place and the compressed charge between the pistons flows around the plate D of the left hand piston, opens the flexible edge E¹ of this piston and occupies the space between it and the cover J. When the cover J has been retracted by the star-wheel T, at point 11, the pistons move together at the same speed to the point 12 for the left hand piston and to point 9 for the right hand piston, and the charge is still further compressed within the left hand combustion chamber. The right-hand piston now makes its exhaust stroke while the left-hand piston remains relatively stationary, the left hand groove moving relatively to its roller from 12 to 8. When the roller of the left hand piston arrives at point 8 ignition is caused to take place in the following manner.

During the last part of the exhaust and compression stroke just described, the sleeve 36 surrounding the left-hand piston rod Q enters the annular space L between the rod Q and cover J still further compressing within it a part of the already compressed air charge. Since this air was highly heated before by compression as well as by contact with the heated piston and cylinder parts and cover J it now becomes sufficiently heated by compression in the annular space L to effect the ignition of the charge. For this purpose it is led from the said space L by way of passage 3 (see Fig. 1, right-hand end) above the ball valve 2. At this time the valve 2 is being raised from its seat by a jet of petrol forced through passage 7 by the pump K and the highly heated air, flowing around the ball valve 2 vaporizes the petrol issuing into the annulus 5 and flows with it through passage 6 to the explosion chamber between the piston D and the cover J, where a charge of compressed air is ready to burn it effectively. The operation then begins anew. At each outward stroke, fresh air is sucked through the hollow piston rod Q, entering the cylinder by way of the chamber E between the piston body D² and the flexible face plate D and between the latter and the flexible margin E¹ of the piston the said plate D acting as a valve and being movable, either by bending or sliding relatively to the former, upon screws E², and opening inwardly only.

Claims:

1. In an internal combustion engine, in combination, a stationary cylinder, a pair of pistons adapted to reciprocate therein, hollow piston rods on said pistons, a cam roller carried by each piston rod, a cam-member adapted to rotate about said stationary cylinder, means for supporting said cam-member, a pair of cam-grooves in said cam-member adapted to engage the cam-rollers

- each cam groove comprising successively a forward helical part of proportional axial length 12, a return helical part of proportional axial length 11, a forward helical part of proportional axial length 1, a return helical part of proportional axial length 2, a cylindrical part connecting the first of said helical parts and the last of said helical parts, and means for operating the said pistons, substantially as described. 10
2. In an internal combustion engine, in combination a stationary cylinder, a pair of pistons adapted to reciprocate therein, piston rods on said pistons, axial passages through said pistons and piston rods, non-return valves opening said passages on the plane sides of the piston, side to side passages leading from the plane sides of the pistons to the rod sides thereof, non-return valves opening said side to side passages to the rod sides of said pistons, cam-rollers carried by said pistons and piston rods, a cam-member adapted to rotate about said stationary cylinder, a pair of irregular zig-zag cam grooves in said cam-member adapted to engage said cam-rollers, means for supporting said cam-member and means for operating the said pistons, substantially as described. 15
- 20
- 25
- 30
- 35
- 40
- 45
- 50
- 55
- 60
- 65
- each cam groove comprising successively a forward helical part of proportional axial length 12, a return helical part of proportional axial length 11, a forward helical part of proportional axial length 1, a return helical part of proportional axial length 2, a cylindrical part connecting the first of said helical parts and the last of said helical parts, and means for operating the said pistons, substantially as described. 10
2. In an internal combustion engine, in combination a stationary cylinder, a pair of pistons adapted to reciprocate therein, piston rods on said pistons, axial passages through said pistons and piston rods, non-return valves opening said passages on the plane sides of the piston, side to side passages leading from the plane sides of the pistons to the rod sides thereof, non-return valves opening said side to side passages to the rod sides of said pistons, cam-rollers carried by said pistons and piston rods, a cam-member adapted to rotate about said stationary cylinder, a pair of irregular zig-zag cam grooves in said cam-member adapted to engage said cam-rollers, means for supporting said cam-member and means for operating the said pistons, substantially as described. 15
3. In an internal combustion engine, in combination, a stationary cylinder, a pair of pistons having inclined corrugated rod-side peripheral portions adapted to reciprocate therein, piston rods on said pistons, axial passages through said pistons and piston rods, inwardly opening non-return valves controlling said axial passages, passages leading from the plane sides of the piston to the rod sides thereof and controlled by the corrugated peripheral piston portions, a cam-member adapted to rotate about said stationary cylinder, a pair of irregular zig-zag cam grooves in said cam-member adapted to engage said cam-rollers, means for supporting said cam-member and means for operating said pistons, substantially as described. 20
4. In an internal combustion engine, in combination, a stationary cylinder, a pair of pistons adapted to reciprocate therein, piston rods on said pistons, axial passages through said pistons and piston rods, non-return valves opening said passages on the plane side of the pistons, annular passages leading from the plane sides of the piston to the rod sides thereof, annular non-return valves opening said annular passages to the rod sides of said pistons, cam-rollers carried by said piston rods, a cam-member adapted to rotate about said stationary cylinder, a pair of irregular zig-zag cam-grooves in said cam-member adapted to engage the said cam-rollers, means for supporting the said cam-member and means for operating the said pistons, substantially as described. 25
5. In an internal combustion engine, in combination, a stationary cylinder, movable cylinder heads therein, seats in said cylinder for said cylinder heads, a pair of pistons adapted to work in said cylinders, hollow piston rods on said pistons, cam-rollers carried by the piston-rods, a cam-member adapted to rotate about the said stationary cylinder, a pair of irregular zig-zag cam-grooves in said cam-member adapted to engage said cam-rollers, internal teeth on said cam-member adapted to intermittently engage means for opening and closing said cylinder heads at each end of the cylinder alternately, means for supporting said cam-member and means for operating said pistons, substantially as described. 30
6. In an internal combustion engine, in combination, a stationary cylinder, inwardly opening cylinder heads and guiding means for said heads therein, seats in said cylinder for said heads, dog-links carried by said heads, shafts having crank-pins adapted to work in said dog-links, star-wheels on said shafts, a pair of pistons adapted to reciprocate in said cylinders, hollow piston rods on said pistons, cam-rollers carried by said piston-rods, cam-member adapted to rotate about said cylinder, a pair of irregular zig-zag cam-grooves in said cam-member adapted to engage said cam-rollers, internal teeth on said cam-member adapted to intermittently engage the said star-wheels, means for supporting said cam-member and means for operating said pistons, substantially as described. 35
7. In an internal combustion engine, in combination, a stationary cylinder, rotating elliptical cylinder heads therein, seats having elliptical apertures in said cylinders for said elliptical heads, shafts for carrying said elliptical heads, helical teeth on said shafts, transverse shafts having teeth adapted to mesh with said helical teeth and having also star-wheels, means for supporting the shafts, a pair of pistons adapted to reciprocate in said cylinder, hollow piston rods on said pistons, cam-rollers carried by said piston-rods, a cam-member adapted to rotate about said cylinder, a pair of irregular zig-zag cam-grooves in said cam-member adapted to engage said cam-rollers, internal teeth on said cam-members adapted to intermittently engage the said star-wheels, means for supporting the said cam-member and means for operating said pistons, substantially as described. 40
8. In an internal combustion engine in combination, a stationary cylinder, heads to said cylinder, a pair of pistons adapted to reciprocate in said cylinder, hollow piston rods on said pistons, cam-rollers carried by said hollow piston rods, means for compressing gas within each end of said cylinder, a stationary annularly grooved expand- 45

- ing sleeve surrounding each piston rod, an annularly grooved expanding sleeve secured to each piston rod, with its groove facing the groove of the stationary sleeve, a sleeve 5 affixed to each cylinder head and surrounding one of said stationary sleeves and a piston-sleeve at the outer end of each piston stroke, a passage connecting the annular groove in a stationary sleeve with an inlet 10 to a gas carbureting means, a passage connecting an outlet for carbureted gas from said gas carbureting means with the interior of one end of the said cylinder, a cam-member adapted to rotate about said cylinder, 15 means for supporting said cam-member, irregular zig-zag cam grooves in said cam-member adapted to engage said cam-rollers and means for operating said pistons, substantially as described.
- 20 9. In an internal combustion engine, in combination, a stationary cylinder, a pair of pistons adapted to reciprocate in said cylinder, hollow piston rods on said pistons, cam-rollers carried by said hollow piston rods, means for compressing gas within each end of the cylinder, means for more highly compressing gas from the cylinder ends, a storage chamber, a delivery passage 25 for conducting gas from the said means for more highly compressing gas to an inlet to a carbureting means and also to a passage opening to said storage chamber, a manually opening check-valve adapted to normally close the said passage opening to the 30 storage chamber, a passage connecting an outlet from said carbureting means with the space within one end of the cylinder, a cam-member adapted to rotate about said cylinder, means for supporting said cam-member, a pair of irregular zig-zag cam- 35 grooves in said cam-member adapted to engage said cam-rollers and means for operating said pistons, substantially as described.
- 40 10. In an internal combustion engine, in combination, a stationary cylinder, a pair 5 of pistons adapted to work therein, means for operating the said pistons, hollow piston rods on said pistons, cam-rollers carried by said piston-rods, each cam-roller being a portion of a cone whose apex coincides with 50 the intersection of the cam-member and the cam-roller axes, a cam-member adapted to rotate about said cylinder, means for supporting said cam-member and irregular zig-zag cam-grooves in said cam-member adapted to engage said cam-rollers, substantially as described.
- 55 11. In an internal combustion engine, in combination, a stationary cylinder a pair of pistons adapted to reciprocate therein, a hollow piston rod on each of said pistons, means for operating the pistons, a pair of cam-rollers carried by each of said piston-rods, each cam-roller of a pair being mounted 60 on a journal that is eccentric to the other journal of the pair, a cam-member adapted to rotate about said cylinder, means for supporting said cam-member and irregular zig-zag cam-grooves in said cam-member each adapted to engage one of said pairs of cam-rollers, substantially as described.
- 65 12. In an internal combustion engine, in combination, a stationary cylinder, a pair of pistons adapted to reciprocate therein, a hollow piston rod on each of said pistons, means for operating the pistons, a cam-roller carried by each piston-rod, a cam-member adapted to rotate about said cylinder means for supporting said cam-member and irregular zig-zag cam-grooves in said 70 cam-member each adapted to engage a cam-roller and each having a laterally adjustable section, substantially as described.
- 75 In testimony whereof I affix my signature in presence of two witnesses.
